(57) CLAIM

The ornamental design for a wireless remote housing, as shown and described.

DESCRIPTION

FIG. 1 is a perspective view of an illustrative wireless remote housing; and,

FIGS. 2-7 are front, back, left, right, top and bottom views, respectively, of the wireless remote housing of FIG. 1.

The portions illustrated in broken lines on the figures are for illustrative purposes only and form no part of the claimed design.
